(57) **CLAIM**

The ornamental design for a toy bus, as shown and described.

DESCRIPTION

FIG. 1 is a left front perspective view of a toy bus showing our new design;

FIG. 2 is a right rear perspective view thereof;

FIG. 3 is a left side elevational view thereof;

FIG. 4 is a right side elevational view thereof;

FIG. 5 is a top plan view thereof;

FIG. 6 is a front elevational view thereof; and,

FIG. 7 is a rear elevational view thereof.

The broken lines illustrate portions of the toy bus that form no part of the claim.
